Inventor

By his Attorney Haworth

UNITED STATES PATENT OFFICE.

EDWIN C. KUBLER, OF SPRINGFIELD, NEW YORK, ASSIGNOR TO AMERICAN LEAD PENCIL COMPANY, A CORPORATION OF NEW YORK.

DESIGN FOR A DISPLAY STAND FOR PENCILS.

Application filed November 27, 1922. Serial No. 4,407. Term of patent 3½ years.

To all whom it may concern:

Be it known that I, EDWIN C. KUBLER, a citizen of the United States, residing at Springfield, Long Island, State of New York, have invented a new, original, and ornamental Design for Display Stand for Pencils, of which the following is a specification, reference being had to the accompanying drawing, forming a part hereof.

What I claim is—

The ornamental design for a display stand for pencils, as shown.

EDWIN C. KUBLER.
